JOINT FOR STRUCTURAL FRAMEWORK

Samuel F. McIntosh, Scarsdale, N. Y.

Application February 4, 1944, Serial No. 521,044

5 Claims. (Cl. 189—36)

This invention has reference to structural steel framework such as is generally used in the erection of modern large buildings and is directed more particularly to a novel type of joint constituting an improved means for connecting together the beams, girders and columns of the framework.

With reference to the erection of structural steel framework, some of the principal advantages which are attained by the type of joint taught by this invention are; the elimination of bolts and rivets and the noise incident to the riveting of the connections during the erection of the structure; to make it possible to assemble on the ground at the site of the building all of the beams and girders which make up each bay of each floor with all of the joints thereof fully locked so that said assemblages may be readily hoisted as units, disposed in juxtaposition to the columns and expeditiously secured in place by using the same type of joints for connecting the girders with the columns; embodying in the joint features of construction by virtue of which the elements thereof when interengaged with each other function to "true up" or plumb and square the framework; the accomplishment of the major portion of the form work on the ground and at a substantial saving in the cost thereof; the simplification of the erection of the framework and its completion in a considerably lesser period of time than heretofore, while requiring less complicated and simpler equipment than previously required, thus effecting an enormous saving in the overall cost of erection of the framework.

Other features of the invention reside in the provision of an improved joint of the indicated character which is adaptable to any architect's plan; which complies with building codes; which requires no testing of parts; which permits of computation of all stresses using standard practice; which simplifies shop detailing; which allows all welding to be done in the shop; which necessitates no punching of parts exceeding twenty pounds; which requires no special shop equipment; and which allows the painting of all parts in the shop by a dip process after the welding has been done.

With the above enumerated and other objects in view, the invention is set forth in greater detail in the following specification, particularly pointed out in the appended claims and illustrated in the accompanying drawing, in which:

Fig. 1 is a fragmentary vertical sectional view

through a structural steel framework equipped with a joint constructed in accordance with the invention and illustrating the same connecting girders with a column.

5. Fig. 2 is a horizontal sectional view taken approximately on the line 2—2 of Fig. 1.

Fig. 3 is a collective perspective view of the angle plate elements of one of the joints showing the same in separated juxtaposition.

10. Fig. 4 is a vertical fragmentary sectional view illustrating the improved joint for establishing a connection between a girder and a beam.

Fig. 5 is a fragmentary sectional plan view taken approximately on a plane indicated by 15. the line 5—5 in Fig. 4.

Referring to the drawing by characters of reference, A designates generally a column including the usual web 10 and flanges 11, while B designates a girder including the web 12 and 20 the flanges 13.

The joints, constituting the present invention, are designed for the purpose of establishing connections between the columns A and the girders B or between the girders and beams or

25 other members of a structural framework, and each joint consists of a pair of angle plate elements C and D which may be produced from standard angle stock of the desired width. As shown in Figs. 1 and 2, the angle plate elements

30 C are secured respectively to the web 10 and to one of the flanges 11 of the column A, said elements being preferably employed in vertically spaced pairs.

Each angle plate element C includes a horizontal web portion 15, an inner flange portion 16 depending from the inner edge of the web portion and an outer flange 17 extending upwardly from the outer edge of the web portion, said outer flange 17 being formed with a medial

40 tongue portion 18 of reduced width with reference to said flange and projecting upwardly from the upper edge thereof so that the portions of the upper edge of said flange 17 which lie on opposite sides of the tongue define supporting shoulders 19, the purpose of which will be hereinafter set forth.

Each of the angle plate elements D consists of a vertical web portion 20 which corresponds in height to the height of the outer flange 17 of the 50 angle plate element C. The element D includes a lower horizontal flange portion 21 projecting inwardly from the lower edge of the web portion 20 and an upper horizontal flange portion 22 extending outwardly from the upper edge of said web portion 20. The lower flange portion 21 cor-

responds in length substantially to the length of the web portion 15 of the element C, while the upper flange portion 22 is formed with a transverse slot 23 which slot is of approximately the same size and shape as the cross-sectional size and shape of the tongue 18 so as to receive said tongue and snugly fit the lower portion of the same with the upper portion of the tongue protruding above the flange 22, when the elements C and D are interengaged or nested as shown in Figs. 1 and 2. The under surface portions of the flange 22 adjacent the slot 23 are adapted to rest upon the shoulders 19 of the flange 17 when the elements C and D are interengaged, while the flange 21 rests upon and flatly contacts with the web 15 and the web 20 is disposed parallel to and contiguous with the flange 17.

In practice, the inner face of the depending flange 16 of each angle plate element C is flatly abutted against and anchored to the web 10 or the flange 11 of the column A, as illustrated, preferably by fillet welding the same thereto as at 24 along the lower and side edges of the flange 16, with the web 15 disposed horizontally and projecting outwardly from the upper edge of said flange and with the outer flange 17 extending upwardly in spaced parallel relation to the web or flange of the column.

The upper horizontal flanges 22 which extend outwardly from the upper edges of the webs 20 of the elements D, are disposed respectively in flat contact with the upper and lower surfaces of the flanges 13 of the girder B, and, as shown, are anchored thereto preferably by fillet welding the same around the sides and outer edges thereof as at 24 so as to secure the elements D to the flanges 13. The upper flanges 22 project horizontally outward from the ends of the girders, with the webs 20 depending therefrom, while the lower flanges 21 protrude horizontally outward from said webs 20. After the girders B are hoisted into place with the webs and flanges of the angle plate elements C and D nested with each other and with the slots 23 engaged over the tongues 18, a wrench of suitable length to provide the necessary leverage and having a socket at one end thereof adapted to fit over the protruding end of the tongues 18, is employed for bending the ends of the tongues to a ninety degree angle, as shown, thereby establishing the locking of the girders in connected relation to the columns. It will thus be apparent that the loads are carried by the welded connections between the flanges 16 of the angle plate elements C and the webs or flanges of the columns A, by imposing a direct downward thrust on said welded connections so as to minimize eccentric stresses or strains which would tend to pull the flanges 16 away from the columns.

The use of the angle plate elements C and D for connecting the beams E to the girders B is illustrated in Figs. 4 and 5 of the drawing, wherein said joints function in the same manner as set forth in connection with their use for connecting the girders to the columns. In this instance the flange 16 of the element C is welded to the web 12 of the girder and preferably only a single joint is employed for connecting each end of the beam to the girders. It therefore follows that the flange 22 is formed with a medial notch 25 in its outer edge and if desired the web 26 of the beam may be provided with a corresponding intermediate notch 27, which notches straddle the adjacent portions of the web and flange and are anchored in associated relation by means of fillet

welding 28. When thus connected with the beams E the elements D have the flanges 22 projecting outwardly beyond the ends of the beams with the webs 20 of said elements depending therefrom and the lower flange projecting outwardly from the lower edge of said web.

It will thus be apparent that by means of the type of joint disclosed, the girders B and beams E which make up each bay of each floor may be assembled on the ground at the site of the building and securely locked together by bending the tongues 18 to locking position, while the form work for the flooring may be applied, after which said assemblage may be readily hoisted as a unit, disposed in juxtaposition to the columns and secured thereto by connecting the girders therewith in the manner previously described.

In some instances and if desired, the outer edges of the lower flanges 21 of the angle plate elements D of the joints which connect the girders with the columns may be welded to the webs 10 or flanges 11 thereof either as auxiliary locking means to supplement the locking action of the tongues 18 or in lieu of the bending of the tongues for this purpose. It is also possible to employ such welding on the joints which connect the beams E with the girders B and this may be resorted to in instances where the angle plates C and D are constructed of angle stock of an excessive thickness. It will also be apparent that the welding of the angle plate elements to the members of the framework can all be done in the shop and that after the welding, the members may be expeditiously and economically painted by a dipping process, thus avoiding the expense and time involved in painting the structure after erection. It is also obvious that due to the close fit of the tongues 18 in the slots 23 and the close tolerance to which the joints may be worked, said joints will function as a means for "truing up" the framework so as to plumb and square the same.

What is claimed is:

1. In a joint for establishing a connection between the column, girder and beam members of structural framework, interengageable angle plate elements secured respectively to the members to be connected, one of which elements includes a horizontal web portion, an inner flange portion depending from the inner edge of the web portion anchored to one structural member with the horizontal web portion projecting outwardly therefrom, and an upstanding outer flange portion at the outer edge of the web portion having a medial upwardly projecting tongue of reduced width with reference to the flange, the other angle plate element including a vertical web portion corresponding in height to and disposed in flat contact with the inner face of the outer flange of the first mentioned element, a lower horizontal flange portion extending inwardly from the lower edge of the web portion thereof and corresponding approximately in length to and arranged in flat contact with and superimposed upon the web portion of said first mentioned element, and an upper flange portion at the upper edge of the web portion projecting outwardly therefrom and anchored to another structural member and formed with a slot corresponding in size and shape to the cross sectional size and shape of and receiving therethrough the tongue of the first mentioned angle plate element and which tongue is bent at an angle to lock the elements of the joint in interengaged nested relation for connecting together the structural members to which said elements are secured.

2. In a joint for connecting together the members of a structural framework, a pair of angle plate elements each including a base portion welded respectively to the members to be connected and each base portion having an angulated portion which angulated portion of one element is nested with the angulated portion of the other element, the base portion of one of said elements having a slot and the angulated portion of the other element having a tongue engaging through the slot of the base portion of the first mentioned element with the free terminal of said tongue protruding from the slot thereof, the free terminal of said tongue being bent to overlie the base portion of the first mentioned slotted element adjacent the slotted portion thereof for locking the elements in nested relation and for securing the framework members connected.

3. A joint for connecting structural framework members together including a pair of mating elements respectively secured to said members and having angulated nested portions, one of said elements having a slot, and a tongue projecting from the other element and engaging through said slot with the terminal of said tongue protruding from the slot and bent into overlying engagement with the first mentioned element adjacent to the slot for locking the elements in nested relation to thereby connect the members of the framework to which the elements are secured.

4. In a joint for connecting the column and

girder members of structural framework, a pair of mating coupling elements for each joint respectively secured to each adjacent pair of structural members, the elements of each pair having nested angulated portions, one element of each pair having a slot, and a tongue projecting from the other element of each pair with the tongue engaging through the slot of its mating element, said tongue being of a cross-sectional size and shape corresponding approximately to the size and shape of the slot and snugly fitting the same so as to square and plumb the framework.

5. In a joint for connecting and locking together the girder and beam members of a structural framework which make up each bay of each floor to facilitate hoisting of the same into place as a unit, a pair of mating coupling elements for each joint respectively secured to the girders and to the opposite ends of the beams, said elements of each pair having nested angulated portions, one element of each pair having a slot and a tongue projecting from the other element of said pair with a portion of said tongue engaging within the slot and with the terminal of said tongue protruding from the slot and bent to overlie and engage with said first mentioned element adjacent to the slot so as to lock the nested portions of the elements in mated relation and thereby connect the girder and beam members together as a unit.
